 DISPENSING CLOSURE
 T. J. Duke Russell, 609 Las Lomas Ave.,
 Pacific Palisades, Calif.
 Filed Dec. 15, 1964, Ser. No. 418,509
 2 Claims. (Cl. 222—545)

This invention has to do generally with closures and particularly with a dispensing closure for use on a collapsible tube or other non-rigid container for controlling the dispensing of paste, viscous liquids or the like.

An object of the invention is to provide a new and improved closure especially designed for use in dispensing material of viscous or paste-like consistency that can be readily operated and which provides a unique sealing effect when closed.

Another object is to provide a closure which operates to pinch off the material being dispensed and which provides a wide sealing closure surface when closed.

A further object is to provide a simple, two-part cap or end housing and closure element construction which can be readily assembled by initially forcibly engaging the parts after which the parts remain operatively engaged.

Still another object is to provide a dispensing closure cap and construction which can be substituted for the original closure cap of the container or which can be originally applied to the container as a removable closure cap, or which can be integrally incorporated into the container itself.

Another object is to provide a construction which lends itself to being designed in a variety of attractive shapes that can readily be wiped clean.

A further object is to provide an integral sealing element in a closure member which provides an effective seal between the closure member and a container upon which it is mounted, thereby eliminating the need for a separate sealing liner as required in conventional caps.

These and other objects will be apparent from the drawing and the following description. Referring to the drawing:

FIG. 1 is an isometric view of a device embodying the invention shown in closed position;

FIG. 2 is a view similar to FIG. 1, but shown in open position;

FIG. 3 is a plan view of the device in closed position, but on a larger scale;

FIG. 4 is a sectional view on line 4—4 of FIG. 3;

FIG. 5 is an isometric view of the closure element;

FIG. 6 is an inverted plan view of the device;

FIG. 7 is a fragmentary sectional view of a portion of the device on the same plane as FIG. 4, but on a larger scale;

FIG. 8 is a side elevational view of an alternate form of the invention showing the dispensing closure integral with a collapsible plastic tube; and

FIG. 9 is a side elevational view, partly in section, of a modified cap suitable for use on wide-mouthed non-rigid containers.

More particularly describing the invention, in FIGS. 1-7 numeral 11 generally designates a cap which may be formed of a suitable non-rigid plastic, such as polyethylene, polypropylene, or polyallomer. The cap includes a generally tubular section 12 which is shown as internally threaded at 13 so that the cap can be screwed onto the threaded neck 14 of a container 15, such as a tube of toothpaste or the like. Beyond the tubular section 12 and extending through the outer end 16 thereof is a dispensing opening 18 which is shown as having flat, parallel side walls 19 and a flat but somewhat laterally inclined or outwardly flared side wall 20. The opposite side of the opening is defined by convex wall 21. The shape of walls 20 and 21 is not critical.

Extending across the outer end 16 of the body and longitudinally therein for a substantial distance in intersecting relation with the opening 18 is a transverse slot 22. This is characterized by parallel side walls 23 which are in 5 the same planes, respectively, and form a continuation of the side walls 19 of opening 18. The base or inner edge of the slot is defined by surfaces 24 and 25 between which I provide a recess 26. The sides of the recess are defined by continuations of the side walls 23 of the slot and by a wall 27 which is semicylindrical, extending somewhat more than 180°.

I provide a closure element 30, also made of a suitable plastic which may be the same material as the body. This closure element is flat-sided having parallel sides 31 which 15 are closely received in the slot in friction engagement therewith. Preferably the turning force required should be of the order of 3-6 in. oz. The closure element is provided with a mounting section 32 on which it pivots and this section is provided with a semicylindrical wall 33 20 of a size such that it complements and fits within the recess 26 of the body. In the assembly of the parts the closure element mounting section is forced into the recess 26 of the cap and hence the material of the cap should have sufficient resiliency for a so-called snap fit of the 25 parts.

Element 30 is provided with a closure face 35 of substantial area which is adapted to engage and seal against the side wall 20 of the opening through the cap. The angle of the face 35 with respect to its position in relation to the pivotal axis of the element is such that the 30 surface engages the wall 20 and is parallel thereto and in full contact therewith when the closure is moved to closed position, as shown in FIG. 4. Preferably the surface 36 outwardly of but immediately adjacent the closure surface 35 should form a continuation of the outer end surface 37 of the cap so that any excess material can be readily wiped from the device. The shape of the remainder of the closure element is not critical, since it is only necessary that it extend beyond the slot 22 sufficiently to be readily engaged by the user. However, the element has been shown as having two long converging edges 38 and 39 which terminate at an outer end surface 40. Also, an edge 41 extends from the mounting section 32 to the sealing surface 35.

Another feature of the invention is the provision of one or more sealing lips 45 at the inner end of the tubular section of the cap. This sealing lip is shown as an annular member which tapers to a featheredge 45' and which is preferably disposed somewhat inwardly at the edge so that 45 it will be engaged and deflected by minimum pressure with the entrance of the end portion 14 of a container 15 upon which the cap is mounted.

In the operation of the device it will be apparent that by making the parts fit sufficiently tightly the closure element will remain closed but at the same time can readily be operated by a pressure of a finger on the end of the element. When the paste or other material has been dispensed, the element is pivoted to the closed position, thereby nipping off the material and effectively sealing the opening. Any excess material can be readily wiped off the surfaces 36 and 37.

In FIG. 8 I show a closure built into and integral with a collapsible tube 50, the closure in this case including the aforementioned closure element 30 and a body 51 in place of the aforementioned cap, the body being integral with the container. The body is provided with a dispensing opening and slot as in the cap previously described.

In FIG. 9 I show a modification designed for relatively 70 large-mouthed non-rigid containers. In this form of the invention the cap, 55, has a large internally threaded tubular section 56 and beyond this an extension 57 correspond-

ing to the outer end portion of the cap previously described in which is mounted a closure element 30.

Although I have illustrated and described a preferred form of my invention, I contemplate that various changes and modifications can be made therein without departing from the invention, the scope of which is indicated by the following claims.

I claim:

1. A dispensing closure construction for a container, comprising a body portion adapted to form an end on a container, said body portion having a transverse axial slot extending inward from the outer end and one side thereof, said body portion having an opening extending from its inner end to and merging with said slot, said slot being defined in part by flat parallel side walls and by an end wall within the body portion, said body portion being formed to provide a concave semicylindrical wall extending through somewhat more than 180° located laterally of said opening, said semicylindrical wall defining a recess facing the outer end of the body portion and open to said slot, and a flat-sided closure element closely received in said slot and having a pivotal mounting portion complementary to and received in said recess, said closure element having a first portion extending from its pivotal mounting portion toward said end wall and terminating in a closure face for engagement with said end wall, said closure element having a second portion extending oppositely to said first portion and so shaped and sized with respect to said body portion as to allow for limited pivotal movement of the closure element in a direction such that said closure face becomes spaced from said end wall to permit escape of contents through said opening and slot.

2. A dispensing closure for a container, comprising a cap having an internally threaded cylindrical inner end portion and having an outer end portion unitary therewith, said outer end portion having a transverse axial slot extending inward from the outer end and one side thereof, said outer end portion having an opening extending from

the interior of said inner end portion to and merging with said slot, said slot being defined in part by flat parallel side walls and by an end wall within the outer end portion, said outer end portion being formed to provide a concave semicylindrical wall extending through somewhat more than 180° located laterally of said opening, said semicylindrical wall defining a recess facing the outer end of the body portion and open to said slot, and a flat-sided closure element closely received in said slot and having a pivotal mounting portion complementary to and received in said recess, said closure element having a first portion extending from its pivotal mounting portion toward said end wall and terminating in a closure face for engagement with said end wall, said closure element having a second portion extending oppositely to said first portion and so shaped and sized with respect to said body portion as to allow for limited pivotal movement of the closure member in a direction such that said closure face becomes spaced from said end wall to permit escape of contents through said opening and slot.
